J. W. McNEICE

CAR DOOR CONSTRUCTION

Filed April 15. 1921

WITNESS: J.W. Ely

BY Victor J. Evans

ATTORNEY

UNITED STATES PATENT OFFICE.

JAMES W. MCNEICE, OF RIDGEFIELD PARK, NEW JERSEY.

CAR-DOOR CONSTRUCTION.

Application filed April 15, 1921. Serial No. 461,475.

To all whom it may concern:

Be it known that I, JAMES W. MCNEICE, a citizen of the United States, residing at Ridgefield Park, in the county of Bergen 5 and State of New Jersey, have invented new and useful Improvements in Car-Door Constructions, of which the following is a specification.

This invention relates to car doors and to 10 some extent car construction.

Some of the objects of the present invention are: to equip a car with a door so constructed as to be movable into and out of the door opening of the car to facilitate the loading and the unloading of the car; to equip a car with a door which allows the car to be readily loaded with a granular commodity such as grain, and which allows the ready unloading of such commodity from the car; 20 to equip a car with a door of hingedly related sections, swingingly supported so as to be movable into the door opening, and out of the door opening to a point adjacent the top of the car; to provide a car with a door 25 or doors having openings therein covered by slides which are movable to uncover the said openings to facilitate unloading operations, and means for holding the slides against movement in either of their positions. With 30 these and other objects in view the invention resides in the particular provision, construction and relative dispositions of the parts hereinafter more fully described and illustrated in the accompanying drawing, in 35 which:

Figure 1 is a side elevation of a freight car equipped with a door of the present invention—a part of the car being shown.

Figure 2 is a vertical sectional view taken 40 on the line 2—2, Figure 1.

Figure 3 is a horizontal sectional view taken on the line 3—3, Figure 1.

Figure 4 is a view illustrating the manner in which the door may be folded upon itself 45 and be suspended at a point adjacent the top of the car.

At the outset it is to be understood that freight cars usually have door openings at the opposite sides thereof, and therefore a door constructed in accordance with the present invention will be arranged for use 50 at each of said door openings. It is also to be understood that the usual sliding or rolling door is to be retained in conjunction with the employment of the door of the present invention.

In the drawing a part only of a freight car 10 is shown. The car 10 is equipped with the usual door 11 and has door openings, such as the door opening 12. Door jambs 13 60 are arranged at the door opening 12. The jambs are rabbeted to receive the side edges of the door 14. The door 14 comprises sections 15 and 16 which are hingedly connected together as at 17. The section 16 has 65 openings 18 therein. Doors or slides 19 are arranged to move over the openings to close the same, and the slides are movable above the openings to uncover the same. The slides 19 are arranged to move in guide ways 70 formed by the use of strips 20 which are secured to the section 16. Each of the slides 19 has a handle 21 and a stop-lug 22. Arranged for swinging movement on the section 16 are latch members 23. An end of 75 each member 23 is hingedly connected to a bolt 24 carried by a bracket 25 secured to the section 16. The free end of each of the members 23 is provided with a slot 26. Securing devices 27 in the nature of latch 80 elements are secured on the section 16 and coact with the ends of the members 23 by virtue of the slots 26, that is to say, by turning the part 28 of each of the devices 27 to one position, the members may be held 85 against outward swinging movement and by turning the part 28 of each device 27 to another position the members may be removed from engagement with said parts 28. It should now be obvious that when the slides 90 19 are disposed to cover the openings 18, the members may be brought over and above the stop-lugs 22 on the said slides to prevent the slides 19 from moving upwardly; and by moving the members 23 from their locked 95 positions out of engagement with the stop-lugs 22, the slides 19 may be moved upwardly to uncover the openings 18. When moved to uncover the openings 18, the handles 21 or parts thereof will be disposed so 100 as to be engageable by the members 23 brought to their locked positions.

In order that the door 14 may be swung in its entirety from one position to another, the section 15 of the door has secured in 105 place thereon members 29 by the use of straps 30. Each of the members 29 has an end angularly disposed portion 31 and the opposite end is connected to a rod or bar 32 attached to the top longitudinal 33 of the 110 car. It will be noted that the door 14 does not entirely close the door opening 12 so that

granular commodities such as grain may be loaded with the well known chutes over the top of the door.

In order that the door 14 may be held or supported at a point adjacent the top 34 of the car, a swingingly mounted member 35 is secured to the top 34. As stated, the sections 15 and 16 of the door 14 are hingedly related, it should therefore be manifest that the sections 15 and 16 may be brought together in overlapped relation as shown in Figure 4, and may be supported by the member 35 with the portions 31 of the members 29 in engagement with the said member 35.

When in such position the door 14 is out of the way to allow the car to be completely cleaned, or the entire contents thereof removed; the door supported adjacent the top also allows the car to be used for transporting any other kind of merchandise.

In order that the door may be locked from the inside against movement there is provided sliding bolts 36 which are carried by the sections of the door 14, and may be made to enter holes or openings in the jambs 13.

The door 14 is to be made preferably

from thin metal plates and it has been found desirable to employ braces 37 which may be detachably connected to the section 16 of the door and to the side of the car. Each brace 37 may include a turnbuckle 38.

What is claimed is:

A car door of the character described comprising a pair of horizontally hingedly connected sections normally arranged one above the other, the lower section being provided with spaced openings, strips secured to the side edges of the openings and providing guideways, sliding doors arranged in the guideways, means for retaining the doors in opened or closed position and said means being in the nature of latch elements including a bracket secured to the lower section between the openings, latch members hingedly connected to said bracket and provided with slots in their free ends and a latch element rotatably mounted upon each outer side of each opening to receive the slotted end of the latch members respectively.

In testimony whereof I hereby affix my signature.

JAMES W. McNEICE.
